UNITED STATES PATENT OFFICE.

CHARLES R. PRATT, OF MONTCLAIR, NEW JERSEY, ASSIGNOR TO THE UNIVERSAL SPEED CONTROL COMPANY, A CORPORATION OF NEW YORK.

PUMP OR MOTOR.

1,163,849.

Specification of Letters Patent. Patented Dec. 14, 1915.

Application filed December 30, 1909. Serial No. 535,646.

To all whom it may concern:

Be it known that I, CHARLES R. PRATT, a citizen of the United States, residing at Montclair, in the county of Essex and State 5 of New Jersey, have invented certain Improvements in Pumps or Motors, of which the following is a specification.

This invention relates to that class of pumps or motors in which an annular series 10 of pistons occupying cylinders therefor in a rotary barrel are connected by piston-rods of uniform length to the disk-like head of a rotary shaft disposed, or adapted to be disposed, at an angle to the axis of rotation of 15 said cylinder barrel, whereby the rotation of said shaft will cause the pistons to pump a fluid or the forcing of a fluid through said cylinders will cause the pistons to rotate the said shaft to which they are connected. A 20 device of this sort is shown in the patent to Holbrook F. J. Porter, No. 985,835, dated March 7, 1911, and my own application Serial No. 489,976, filed April 15, 1909, has to do with the same sort of a pump or motor, 25 the present invention consisting in certain improvements in such a pump or motor.

The objects of the invention are to hold the face or end of the cylinder barrel, through which lead the ports to the piston 30 cylinders, against its seat and which seat is in effect a valve seat; to adapt such holding and the means for doing it to various conditions of velocity and pressure of the fluid passing through the cylinders; to enable the 35 said ports to be of equal or greater area than the cylinders; to thus avoid throttling the flow of fluid and increasing hydraulic friction; to secure minimum leakage in the operation of the pump or motor or rotation of 40 the cylinder barrel against its end seat, and to obtain other advantages and results as may be brought out in the following description.

Referring to the accompanying drawings, 45 in which like numerals of reference indicate corresponding parts in each of the several figures, Figure 1 is a side elevation, partly in central longitudinal section, of a pump or motor of my improved construction especially adapted for conditions where both the 50 pressure and velocity of the fluid are substantially constant; Fig. 2 is a complete central longitudinal section of a pump or motor of my improved construction especially adapted for conditions where either

the pressure or velocity of the fluid varies while the other is substantially constant, taken as to the casing on line 2—4, and as to the cylinder barrel and shaft head on line 22—4, both Fig. 4; Fig. 3 is a central longitudinal section through the pump or motor casing and cylinder barrel at their seat against each other, taken as to the casing on line 3—5 and as to the barrel on line 33—35, both Fig. 4; Fig. 4 is an end view of the 60 pump or motor, and Fig. 5 is a detail perspective view of a certain key detached.

In the pump or motor shown in said prior Porter Patent No. 985,835, the ports of the cylinders opened through the sides of the 70 cylinder barrel, but in still earlier patents, as for instance No. 432,359 to Robert C. Berry, July 15, 1890, the ports have opened through the end of the cylinder barrel and its end seat against the casing of the pump 75 or motor. In this case, the ports were restricted or of less cross-sectional area than the cylinders, for the purpose of holding the face of the cylinder barrel against its seat by the reaction of hydraulic pressure, although by such restriction the flow of fluid was throttled and hydraulic friction increased. However, this was, and still is, the best construction for those conditions 80 where both the pressure and the velocity of the fluid vary widely, but by my present invention I have devised means for using under other conditions the said end ports without the objections stated. For instance, under conditions where both the pressure and the velocity of the moving fluid are substantially constant, I employ the construction especially illustrated in Fig. 1, where 10 indicates the casing of a pump or motor standing upon a foot or base 11. Within the 85 chamber of said casing 10 is located a cylinder barrel 12, said barrel seating at its end against the annular seat plate 13 of the casing, and through which plate the ports lead to the cylinders 36 of the said barrel. The 90 said cylinder barrel 12 is bored centrally and longitudinally, said bore being of larger diameter for the portion of the barrel away from its seat, as at 14, and reduced at its end next the seat end of the barrel, or at 15, and providing an interior shoulder 17. The casing 10 is bored, as at 16, in alignment with the said small portion 15 of the bore of the barrel at its seat end, preferably of 95 the same diameter therewith, and the shank 105 110

18 of a pin 19 extends through said borings, the pin having an enlarged head 20 in the enlarged portion 14 of the boring of the cylinder barrel. The said head 20 is enlarged abruptly from the shank 18 of the pin 19 so as to form a shoulder 21 opposite the said shoulder 17 on the cylinder barrel, and a roller or ball bearing 22 of any suitable and ordinary construction is arranged between 5 said annular shoulders 17 and 21. The outer end of the shank 18, beyond the casing 10, is threaded to receive a nut 23, and obviously by tightening said nut the cylinder barrel can be drawn firmly to its end seat provided 10 by the plate 13. In practice, the barrel is not drawn against the said plate 13, but is left at a distance of about five thousandths of an inch therefrom, so that it does not turn in frictional contact therewith, but 15 upon an interposed film of escaping fluid. Since this construction is used only when the velocity is constantly high, however, it will be understood that the proportion of leakage is so small as to be negligible. This 20 construction permits an unlimited fluid pressure. The said head 20 of the pin 19 is at its end opposite the shank 18 centrally and longitudinally bored to receive the stem 24 which has a ball and socket connection as 25 at 25 to the disk-like head 32 of the shaft 33 to which the rods 34 of the pistons 35 in the cylinders 36 of the barrel 12 are connected, all said parts which are not shown in full 30 lines in Fig. 1 being the same as in Fig. 2 35 where they are clearly shown in detail. Said stem 24 also carries the gear 26 by which the cylinder barrel 12 is caused to rotate with the driving or driven shaft by gear teeth 37 40 on the disk or head 32 thereof, said gear 26 being fast to the stem 24, as by a key 27, and also keyed to the cylinder barrel as at 28, where its sleevelike end 29 enters the portion 14 of the central boring of the cylinder barrel. Where the end of the stem 24 enters 45 the boring 30 of the head 20 of the pin 19, it has a long bearing therein which is suitably provided with a bronze bushing 31.

When the pressure of the fluid does not vary materially, but its velocity varies, it is 50 preferable to seat the cylinder barrel by spring pressure, and such a construction is particularly illustrated in Fig. 2 of the drawings. Here 110 indicates the casing of the pump or motor, having a foot, 111 on which 55 it stands, and 112 is the cylinder barrel arranged in said casing with cylinders 40 in which reciprocate the pistons 41 which are connected by rods 42 to the head 43 of the driving (or driven) shaft 44. 113 is the seat 60 plate against which the cylinder barrel bears at its end and through which open the ports to the cylinders 40, it being remembered that said ports are not less in cross sectional area than the cylinders. The said cylinder bar- 65 rel 112 is centrally and longitudinally cham-

bered, as at 45, and into this chamber projects axially a pin 119 from the casing 110. Within the thickness of the said casing the pin 119 is diametrically reduced to form a shoulder 46 which seats against a 70 corresponding shoulder of the casing, the reduced extremity 47 of the pin projecting out through the casing wall and receiving a nut 123. Thus by tightening up the said nut 123 the pin may be clamped in fixed position. 75

At the end of the pin 119 within the cylinder barrel 112 are exterior annular stop means, which I have shown as consisting of a shoulder or head 48 which takes the thrust of a sleeve comprising two members 49 and 50 which have a spherical bearing against each other. The opposite end of the chamber 45 of the cylinder barrel closes around the pin 119 and provides stop means which I have shown consisting of a collar 51 with a spherical bearing against the bottom of the chamber 45. Between the two stop means just described, one on the pin 119 and the other on the cylinder barrel 112, I arrange 80 a helical spring 52 surrounding the pin 119, and the tension of this spring is such as to hold the cylinder barrel 112 seated against the plate 113. Preferably a ball-thrust bearing 53 and collar 54 are arranged at one 85 end of the spring 52, and washers 55 at the other end. It will be understood, however, that these details could be omitted or varied without departing from the spirit and scope 90 of my invention, and that instead of the somewhat complex stop means which I have 95 described for purposes which will appear hereinafter, other and simpler stop means could be employed as will be apparent to those skilled in the art. 100

When the pressure of the fluid varies materially, obviously the spring 52, which has a constant pressure, will not seat the cylinder barrel at the higher fluid pressures so as to prevent leakage, unless said spring pressure 110 is made so strong as to cause undue friction of the cylinder barrel against its seat at the lower fluid pressures, and under such conditions I reinforce the spring by the pressure of the fluid which is passing through 115 the pump or motor, or might indeed use such pressure without the spring at all. In doing this, the sleeve 49 and collar 51 are packed against the barrel chamber 45 and pin 119, respectively, and between said sleeve and collar the pin is bored transversely, as at 56, to communicate with a central longitudinal passage 57. This passage 57 is, in the solid end portion of the casing 110, intersected by a transverse boring 58 which extends between 120 the inlet and outlet ducts 59, 60, respectively, of the pump or motor for the fluid. (See Fig. 3.) A sliding valve 61 is in said passage 58 and tubular stops 62, 63 are screwed into the opposite ends of the passage to hold 125 130

said valve 61 against escape and form seats therefor. When the valve 61 is seated on one tubular stop it lies entirely on that side of the passage 57 and permits free passage 5 through the other tubular stop into the passage, and obviously it will always be seated upon the tubular stop next the exhaust duct. In other words, the pressure from the cylinder barrel will as it enters the port force the 10 valve 61 over to the other side of the passage 57 and thus admit itself to the chamber 45 of the cylinder barrel. Such pressure acts against the sleeve 49 which is held fixed by the pin 119, and reacts against the collar 51 15 to force it and the cylinder barrel against the seat plate 113, the pressure effective to do this being that against a surface equal in area to the difference between the cross-sectional area of the chamber 45 where the sleeve 49 20 engages it and the pin 119 where it passes through the collar 51. By this arrangement, the pressure of the cylinder barrel 12 against its seat plate 113 is proportional to the pressure of the fluid, which is of value 25 when such pressure of the fluid varies materially.

In Fig. 2, the stem 124 which connects to the head 43 of the driving (or driven) shaft 44 by the ball joint 125, is made fast to the 30 gear 126 by a cross-piece 64, and extends at its end into a longitudinal socket 130 of the pin 119, a bronze bushing 131 being provided for the bearing. Then said stem is rotatably 35 locked to the cylinder barrel 112 by an annular key 65 upon itself between the barrel and gear 126, which key has longitudinal lugs 66 entering recesses in the end of said gear sleeve and radial lugs 67 entering recesses 68 in the barrel. This connection allows 40 the cylinder barrel a limited motion for adjusting itself, while positively rotating it.

A relief duct 69 is shown leading from the casing chamber at one side of the cylinder 45 barrel through the said casing to a central point of the end or seating face of said barrel.

The particular adaptability of the different arrangements which I have shown to the 50 different conditions under which they are to be used, as I have described, will be clearly seen by a brief review of them at this point. The construction of Fig. 1, where the cylinder barrel is held at a fixed clearance from 55 its seat, is simplest and entirely adequate, for example, where the velocity of the liquid in circulation is comparatively high with respect to the pressure and thus the leakage through said clearance space is a very small 60 part of the volume of liquid circulated. If with this construction either the pressure is increased very greatly or the velocity decreased very greatly, the percentage of leakage will become too large.

65 With the construction shown in Fig. 2,

considered only as to the spring and disregarding the means for introducing fluid to act in conjunction with said spring, it will be understood that the cylinder barrel is seated with the least possible clearance, the 70 spring effecting such seating and allowing for wear, and thus there is minimum leakage between the cylinder barrel and its seat and the velocity of the liquid in circulation can thereby be low or vary without the proportion of leakage being excessive. Obviously if also the pressure becomes high or excessive, which is the third case or set of conditions considered in the foregoing part of this specification, such pressure would 75 compress the spring and thus unduly increase leakage between the cylinder barrel and its seat, if no means were provided to prevent it, and for this reason I introduce the fluid pressure into the spring chamber, 80 as described, to assist in holding the cylinder seated under such high or excessive pressures.

Having thus described the invention, what I claim is:

1. The combination with a rotary disk, a rotatable barrel having a plurality of cylinders parallel to its axis, pistons in said cylinders connected to said disk, a support for said barrel providing a seat for the same at 90 its end away from the disk, said support having inlet and outlet ducts and said seat and barrel-end having cooperating ports leading from said ducts to said cylinders, and means for holding said barrel with its axis at an angle to the axis of said disk, of a central pin at the end of said barrel away from its seat pivotally connected to the center of said disk and free to move with the 95 disk independently of the barrel. 100

2. The combination with a rotary disk, a rotatable barrel with its axis at an angle to the axis of said disk and having a plurality of cylinders parallel to its axis, pistons in said cylinders connected to said disk, and a 110 casing inclosing said barrel and providing a seat for the same at its end away from the disk, said casing having inlet and outlet ducts and said seat and barrel-end having cooperating ports leading from said ducts to said cylinders, of a central pin at the end of said barrel away from its seat and pivotally connected to the center of said disk, a sleeve on said pin having one end of itself 115 rotatably fast to the barrel, and cooperating 120 gears on the other end of said sleeve and the disk respectively.

3. The combination with a shaft, a head on said shaft, a rotatable barrel with its axis at an angle to said shaft having a plurality of 125 cylinders parallel to said axis and a central bore, pistons in said cylinders connected to said shaft head, and a casing inclosing said barrel and providing a seat for the same at 130 its end away from the shaft, said casing hav-

- ing inlet and outlet ducts and said seat and barrel end having coöperating ports leading from said ducts to said cylinders of a sleeve projecting from said bore of the rotary barrel rotatably fast with respect thereto, coöperating gears on said sleeve and the shaft head respectively, and a pin inside said sleeve pivotally connected to the center of said shaft head.
10. 4. The combination with a shaft, a head on said shaft, a rotatable barrel with its axis at an angle to said shaft having a plurality of cylinders parallel to said axis and a central bore, pistons in said cylinders connected to said shaft head, and a casing inclosing said barrel and providing a seat for the same at its end or face away from the shaft, said casing having inlet and outlet ducts and said seat and barrel end having coöperating ports leading from said ducts to said cylinders, of a stud projecting from said seat axially into said barrel bore, a sleeve projecting from said bore of the rotary barrel rotatably fast with respect thereto, coöperating gears on said sleeve and the shaft head respectively, and a pin inside said sleeve pivotally connected to the center of said shaft head.
15. 5. The combination with a shaft, a head on said shaft, a rotatable barrel having a plurality of cylinders parallel to its axis and a central bore, pistons in said cylinders connected to said shaft head, a support for said barrel providing a seat for the same at its end away from the shaft, said support having inlet and outlet ducts and said seat and barrel-end having coöperating ports leading from said ducts to said cylinders, and means for holding said barrel with its axis at an angle to said shaft, of a stud projecting from said seat into said barrel bore and a central socket, and a pin in said socket pivotally connected to the center of the shaft head.
20. 6. The combination with a rotary disk, a rotatable barrel with its axis at an angle to the axis of said disk having a plurality of cylinders parallel to its axis and a central bore, pistons in said cylinders connected to said disk, and a casing inclosing said barrel and providing a seat for the same at its end away from the disk, said casing having inlet and outlet ducts and said seat and barrel-end having coöperating ports leading from said ducts to said cylinders, of a stud projecting from said seat into said barrel bore and having a central socket, a pin and sleeve one extending into said socket, said pin being pivotally connected to the center of the said disk, and said sleeve having one end of itself rotatably fast to the barrel, and coöperating gears on the other end of said sleeve and the disk respectively.
25. 7. In a rotary piston unit, the combination with a support providing a seat with inlet and exhaust ports opening there-
- through, a barrel adapted at one end to engage said seat and having an annular series of longitudinal cylinders with ports adapted to register with said ports in the seat and a central bore providing an interior shoulder adjacent to the seat end of the barrel, of a stud projecting from said seat into said barrel bore and having therein a head opposed to said internal shoulder and adapted to coöperate therewith in holding the barrel to its seat.
8. The combination with a rotary disk, a rotatable barrel with its axis at an angle to the axis of said disk having a plurality of cylinders parallel to its axis and a central bore providing an interior shoulder, pistons in said cylinders connected to said disk, and a casing inclosing said barrel and providing a seat for the same at its end or face away from the rotary disk, said casing having inlet and outlet ducts and said seat and barrel end having coöperating ports leading from said ducts to said cylinders, of a stud projecting from said seat axially into said barrel bore and having a head therein opposed to said internal shoulder and adapted to coöperate therewith to seat the barrel, a sleeve projecting from said bore of the rotary barrel rotatably fast with respect thereto, coöperating gears on said sleeve and the disk respectively, and a pin inside said sleeve pivotally connected to the center of said disk.
30. 9. The combination with a rotary disk, a rotatable barrel having a plurality of cylinders parallel to its axis and a central bore, pistons in said cylinders connected to said disk, a support for said barrel providing a seat for the same at its end away from the rotary disk, said support having inlet and outlet ducts and said seat and barrel-end having coöperating ports leading from said ducts to said cylinders, and means for holding said barrel with its axis at an angle to the axis of said disk, of a stud projecting from said seat into said barrel bore and having a head adapted to hold the barrel to its seat, said head having a central socket, and a pin in said socket pivotally connected to the center of the disk.
35. 10. The combination with a rotary disk, a rotatable barrel with its axis at an angle to the axis of said disk having a plurality of cylinders parallel to its axis and a central bore, pistons in said cylinders connected to said disk, and a casing inclosing said barrel and providing a seat for the same at its end away from the disk, said casing having inlet and outlet ducts and said seat and barrel-end having coöperating ports leading from said ducts to said cylinders, of a stud projecting from said seat into said barrel bore and having a head adapted to hold the barrel to its seat, said head having a central socket, a pin and sleeve one extending into said

- socket, said pin being pivotally connected to the center of the disk and said sleeve having one end of itself rotatably fast to the barrel, and coöperating gears on the other end of said sleeve and the disk respectively. 5
11. The combination with a shaft, a head on said shaft, a rotatable barrel with its axis at an angle to said shaft having a plurality of cylinders parallel to said axis and 10 a central bore providing an interior shoulder, pistons in said cylinders connected to said shaft head, and a casing inclosing said barrel and providing a seat for the same at its end or face away from the shaft, said 15 casing having inlet and outlet ducts and said seat and barrel end having coöperating ports leading from said ducts to said cylinders, of a stud projecting from said seat into said barrel bore and having a head therein 20 opposed to said internal shoulder and adapted to coöperate therewith in holding the barrel to its seat, said head having a central socket, a pin in said socket pivotally connected to the center of the shaft head, a 25 sleeve on said pin having one end of itself keyed in said bore of the barrel, and coöperating gears on the other end of said sleeve and the shaft head respectively. 30
12. The combination with a rotary disk, 35 a rotatable barrel having a plurality of cylinders parallel to its axis, pistons in said cylinders connected to said disk, a support for said barrel providing a seat for the same at its end away from the disk, said support having inlet and outlet ducts and said seat and barrel-end having coöperating ports leading from said ducts to said cylinders, and means for holding said barrel with its axis at an angle to the axis of said disk, 40 of a central pin at the end of said barrel away from its seat pivotally connected to the center of said disk and free to move longitudinally with the disk independent of the barrel and its support. 45
13. In a rotary piston unit, the combination with a support providing a seat with inlet and exhaust ports opening therethrough, a barrel adapted at one end to engage said seat and having an annular series 50 of longitudinal cylinders with ports adapted to register with said ports in the seat and a central bore providing an interior shoulder adjacent to the seat end of the barrel, of a stud projecting from said seat and having a head in said bore of the barrel, and a helical spring in said bore between said stud head and interior shoulder. 55
14. In a rotary piston unit, the combination with a support providing a seat with 60 inlet and exhaust ports opening therefrom, a barrel adapted at one end to engage said seat and having an annular series of longitudinal cylinders, with ports adapted to register with said ports in the seat, said barrel having in its end away from said seat 65 an angular recess, of an annular key loose in said recess for turning the barrel, and means for turning said key. 70
15. In a rotary piston unit, the combination with a support providing a seat with inlet and exhaust ports opening therefrom, a barrel adapted at one end to engage said seat and having an annular series of longitudinal cylinders, with ports adapted to register with said ports in the seat, said barrel having in its end away from said seat 75 an angular recess, of an annular key loose in said recess for turning the barrel, a sleeve rotatably fast with respect to said key, and means for turning said sleeve. 80
16. In a rotary piston unit, the combination with a support providing a seat with inlet and exhaust ports opening therethrough, a barrel adapted at one end to engage said seat and having an annular series of longitudinal cylinders with ports adapted to register with said ports in the seat and a central bore providing an interior shoulder adjacent to the seat end of the barrel, of a stud projecting from said seat into said bore of the barrel, stop means on said stud at a distance from said shoulder of the barrel, a sleeve on said stud next said stop means having a spherical bearing thereagainst, a collar on the stud having a spherical bearing against the said shoulder of the barrel, and a spring between said sleeve and collar. 85
17. In a rotary piston unit, the combination with a support providing a seat with inlet and exhaust ports opening therethrough, a barrel adapted at one end to engage said seat and having an annular series of longitudinal cylinders with ports adapted to register with said ports in the seat and a central bore providing an interior shoulder adjacent to the seat end of the barrel, of a stud projecting from said seat into said bore of the barrel, stop means on said stud at a distance from said shoulder of the barrel, a 90 sleeve on said stud next said stop means, a collar on the stud next said shoulder of the barrel, and means for resiliently forcing said collar and sleeve apart. 100
18. In a rotary piston unit, the combination with a support providing a seat with inlet and exhaust ports opening therethrough, a barrel adapted at one end to engage said seat and having an annular series of longitudinal cylinders with ports adapted to register with said ports in the seat and a central bore providing an interior shoulder adjacent to the seat end of the barrel, of a stud projecting from said seat into said bore of the barrel, stop means on said stud at 105 a distance from said shoulder, and means for introducing the pressure fluid into the barrel bore between said shoulder and stop means. 115
19. In a rotary piston unit, the combina- 120
- 125
- 130

- tion with a support providing a seat with inlet and exhaust ports opening therethrough, a barrel adapted at one end to engage said seat and having an annular series 5 of longitudinal cylinders with ports adapted to register with said ports in the seat and a central bore providing an interior shoulder adjacent to the seat end of the barrel, of a stud projecting from said seat axially into 10 said bore of the barrel, opposite sleeves on said stud within said barrel one slidably tight against the barrel and the other against the stud, and means for introducing the pressure fluid between said sleeves.
- 15 20. In a rotary piston unit, the combination with a support providing a seat with inlet and exhaust ports opening therethrough, a barrel adapted at one end to engage said seat and having an annular series of longi- 20 tudinal cylinders with ports adapted to register with said ports in the seat and a central bore providing an interior shoulder adjacent to the seat end of the barrel, of a stud projecting from said seat into said bore 25 of the barrel, stop means on said stud at a distance from said shoulder of the barrel, a sleeve on said stud next said stop means, a collar on the stud next said shoulder of the barrel, and means for introducing the pres- 30 sure fluid between said collar and sleeve.
21. In a rotary piston unit, the combination with a support providing a seat with inlet and exhaust ports opening therethrough, a barrel adapted at one end to engage said 35 seat and having an annular series of longitudinal cylinders with ports adapted to register with said ports in the seat and a central bore providing an interior shoulder adjacent to the seat end of the barrel, of a stud 40 projecting from said seat into said bore of the barrel, stop means on said stud at a distance from said shoulder of the barrel, a sleeve on said stud next said stop means having a bearing thereagainst and slidably 45 tight against the wall of the barrel bore, a collar on the stud engaging said shoulder of the barrel and slidably tight against the stud, and means for introducing the pressure fluid between said collar and sleeve.
- 50 22. In a rotary piston unit, the combination with a support providing a seat with inlet and exhaust ports opening therethrough, a barrel adapted at one end to engage said seat and having an annular series of longi- 55 tudinal cylinders with ports adapted to register with said ports in the seat and a central bore providing an interior shoulder adjacent to the seat end of the barrel, of a stud projecting from said seat into said 60 bore of the barrel, stop means on said stud at a distance from said shoulder, and means for introducing the pressure fluid into the barrel bore between said shoulder and stop means through said stud.
- 65 23. In a rotary piston unit, the combina- 70 tion with a support providing inlet and outlet ducts and a seat with inlet and exhaust ports opening therethrough from said ducts, a barrel adapted at one end to engage said seat and having an annular series of longi- 75 tudinal cylinders with ports adapted to register with said ports in the seat and a central bore providing an interior shoulder adjacent to the seat end of the barrel, of a stud projecting from said seat into said bore 80 of the barrel, stop means on said stud at a distance from said shoulder, said stud having a longitudinal passage opening laterally into the barrel bore between said stop means and shoulder, and the stud and support being bored transversely of the stud between the said inlet and outlet ducts of the support, stops in said boring on opposite sides of the stud, and a sliding valve between said 85 stops.
24. In a rotary piston unit, the combination with a support providing a seat with inlet and exhaust ports opening therethrough, a barrel adapted at one end to engage said seat and having an annular series of longitudinal cylinders with ports adapted to register with said ports in the seat, of means for mechanically exerting a resilient pressure to hold said barrel to its seat, and means for supplementing said pressure by pressure 90 from the fluid passing through the rotary unit.
25. In a rotary piston unit, the combination with a support providing a seat with inlet and exhaust ports opening therethrough, a barrel adapted at one end to engage said seat and having an annular series of longitudinal cylinders with ports adapted to register with said ports in the seat and a central bore providing an interior shoulder 100 adjacent to the seat end of the barrel, of a stud projecting from said seat into said bore of the barrel, stop means on said stud at a distance from said shoulder, a spring between said shoulder and stop means, and 105 means for introducing the pressure-fluid into the barrel bore between said shoulder and stop means.
26. In a rotary piston unit, the combination with a support providing a seat with inlet and exhaust ports opening therethrough, a barrel adapted at one end to engage said seat and having an annular series of longitudinal cylinders with ports adapted to register with said ports in the seat and a central bore providing an interior shoulder 115 adjacent to the seat end of the barrel, of a stud projecting from said seat into said bore of the barrel, stop means on said stud at a distance from said shoulder of the barrel, a sleeve on said stud next said stop means, a collar on the stud next said shoulder of the barrel, a spring between said collar and sleeve, and means for introducing the pressure fluid between said collar and sleeve.

27. In a rotary piston unit, the combination with a support providing a seat with inlet and exhaust ports opening therethrough, a barrel adapted at one end to engage said seat and having an annular series of longitudinal cylinders with ports adapted to register with said ports in the seat and a central bore providing an interior shoulder adjacent to the seat end of the barrel, of 5 a stud projecting from said seat into said bore of the barrel, stop means on said stud at a distance from said shoulder of the barrel, a sleeve on said stud next said stop means having a spherical bearing thereagainst, a 10 collar on the stud having a spherical bearing against the said shoulder of the barrel, a spring between said collar and sleeve, and means for introducing the pressure fluid between said collar and sleeve.
- 20 28. The combination with a shaft, a rotatable member with its axis at an angle to said shaft and having a plurality of cylinders parallel to said axis, pistons in said cylinders connected to said shaft, and a casing 25 inclosing said rotatable member and providing a seat for the same at its end or face away from the shaft, said casing having inlet and outlet ducts and said seat and face having coöperating ports leading from said 30 ducts to said cylinders, said ports of not less cross-section than their respective cylinders, of a pin projecting from the casing axially into the rotatable member, opposite sleeves on said pin within said rotatable member 35 one slidably tight against the member and the other against the pin, and means for introducing the pressure fluid between said sleeves.
29. The combination with a shaft, a rotatable member with its axis at an angle to said shaft and having a plurality of cylinders parallel to said axis, pistons in said cylinders connected to said shaft, and a casing 40 inclosing the said rotatable member and providing a seat for the same at its end or face away from the shaft, said casing having inlet and outlet ducts and said seat and face having coöperating ports leading from said ducts to said cylinders, said ports of not less 45 cross-section than their respective cylinders, of a pin projecting from the casing axially into the rotatable member, opposite sleeves on said pin within said rotatable member 50 one slidably tight against the member and the other against the pin, and means for conducting pressure fluid from said inlet and outlet ducts to the space between said sleeves.
30. The combination with a shaft, a rotatable member with its axis at an angle to said shaft and having a plurality of cylinders parallel to said axis, pistons in said cylinders connected to said shaft, and a casing 55 inclosing said rotatable member and providing a seat for the same at its end or face away from the shaft, said casing having in-
- let and outlet ducts and said seat and face having coöperating ports leading from said ducts to said cylinders, said ports of not less cross-section than their respective cylinders, of a pin projecting from the casing axially 60 into the rotatable member, a stop at the end of said pin away from the seat end of the rotatable member, a sleeve on the pin next said stop comprising two portions having a spherical bearing against each other, said 65 sleeve slidably fitting the rotatable member, a stop at the seat end of the rotatable member, a collar having a spherical bearing against said stop on the rotatable member and slidably fitting the pin, and means for 70 introducing the pressure fluid between said collar and sleeve.
31. The combination with a shaft, a rotatable member with its axis at an angle to said shaft and having a plurality of cylinders parallel to said axis, pistons in said cylinders connected to said shaft, and a casing 75 inclosing said rotatable member and providing a seat for the same at its end or face away from the shaft, said casing having inlet and outlet ducts and said seat and face having coöperating ports leading from said ducts to said cylinders, said ports of not less cross-section than their respective cylinders, of a pin projecting from the casing axially 80 into the rotatable member and having a longitudinal passage opening through its side within said rotatable member, sleeves on said pin within the rotatable member on opposite sides of said passage opening, one sleeve 85 slidably fitting the rotatable member and the other the pin, the casing being bored between its said inlet and outlet ducts transversely of the pin and its said passage, tubular stops in the ends of said boring, and a sliding 90 valve between said stops.
32. The combination with a shaft, a rotatable member with its axis at an angle to said shaft and having a plurality of cylinders parallel to said axis, pistons in said cylinders connected to said shaft, and a casing 95 inclosing said rotatable member and providing a seat for the same at its end or face away from the shaft, said casing having inlet and outlet ducts and said seat and face having coöperating ports leading from said ducts to said cylinders, said ports of not less cross-section than their respective cylinders, of a pin projecting from the casing axially 100 into the rotatable member, opposite sleeves on said pin within said rotatable member 105 one slidably tight against the member and the other against the pin, means for introducing the pressure fluid between said sleeves.
33. The combination with a shaft, a rotatable member with its axis at an angle to said shaft and having a plurality of cylinders parallel to said axis, pistons in said cyl-

inders connected to said shaft, and a casing inclosing said rotatable member and providing a seat for the same at its end or face away from the shaft, said casing having inlet and outlet ducts and said seat having co-operating ports leading from said ducts to said cylinders, said ports of not less cross section than their respective cylinders, of a pin projecting from the casing axially into the rotatable member, a stop at the end of said pin away from the seat end of the rotatable member, a sleeve on the pin next said stop comprising two portions having a spherical bearing against each other, said sleeve slidably fitting the rotatable member, a stop at the seat end of the rotatable member, a collar having a spherical bearing against said stop on the rotatable member and slidably fitting the pin, means for introducing the pressure fluid between said collar and sleeve, and a helical spring on said pin between said sleeve and collar.

34. The combination with a shaft, a rotatable member with its axis at an angle to said shaft and having a plurality of cylinders parallel to said axis, pistons in said cylinders connected to said shaft, and a casing inclosing said rotatable member and providing a seat for the same at its end or face away from the shaft, said casing having inlet and outlet ducts and said seat and face having co-operating ports leading from said ducts to said cylinders, said ports of not less cross-section than their respective cylinders, of means for mechanically exerting a resili-

ent pressure to hold the face of said rotatable member against its said seat, and means for supplementing said pressure by the hydraulic pressure of the fluid passing through the cylinders.

35. In a rotary piston unit, the combination with a support providing a seat with inlet and exhaust ports opening therefrom, a barrel adapted at one end to engage said seat and having an annular series of longitudinal cylinders, with ports adapted to register with said ports in the seat, said barrel having in its end away from said seat an angular recess with radial extensions, an annular key loose in said recess and having lugs projecting into said radial extensions, and means for turning said key.

36. In a rotary piston unit, the combination with a support providing a seat with inlet and exhaust ports opening therefrom, a barrel adapted at one end to engage said seat and having an annular series of longitudinal cylinders, with ports adapted to register with said ports in the seat, said barrel having in its end away from said seat an angular recess with radial extensions, an annular key loose in said recess and having lugs projecting into said radial extensions, a sleeve rotatably fast with respect to said key, and means for turning said sleeve.

CHARLES R. PRATT.

In the presence of—

RUSSELL M. EVERETT,
FRANCES E. BLODGETT.
